CLAIM

The ornamental design for an ultrasonic controller connector, as shown and described.

DESCRIPTION

FIG. 1 is a top, front and right side perspective view of an ultrasonic controller connector showing my new design;

FIG. 2 is a top, rear and left side perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof;

FIG. 8 is a right side elevational view thereof; and,

FIG. 9 is a top, front and left side perspective view thereof, shown in an environment of use, attached to a connector body.

The ultrasonic controller connector is shown with a symbolic break in its length. The appearance of any portion of the article between the break lines forms no part of the claimed design. The broken lines depicting a connector body are for the purpose of illustrating environmental subject matter and form no part of the claimed design.
